UNITED STATES PATENT OFFICE.

FRED WEINECK, OF ST. PAUL, MINNESOTA.

HOT-AIR FURNACE OR HEATER.

Application filed July 5, 1922. Serial No. 572,919.

To all whom it may concern:

Be it known that I, FRED WEINECK, a citizen of the United States, residing at St. Paul, in the county of Ramsey and State of Minnesota, have invented certain new and useful Improvements in Hot-Air Furnaces or Heaters, of which the following is a specification.

My invention relates to hot air furnaces and heaters and the main object is to so construct a device of said kind that it will save fuel by transmitting the greatest possible amount of the heat produced from the fuel into the room or rooms heated by hot air. To this end my apparatus is constructed with an extraordinary large surface for transmitting heat to the air used for heating, and with other facilities for securing the maximum of heat from the fuel used.

20 In the accompanying drawings:

Fig. 1 is a front elevation of my heater in the simple form adapted for use as a heating stove in one or more rooms located on the same floor.

25 Fig. 2 is a partly sectional side elevation of the heater with the ring 7 intact showing how it may be used as a hot air furnace for heating, by hot air, rooms located mainly or only on one floor.

30 Fig. 3 is a partly sectional top view of Fig. 1 or the corresponding portion of Fig. 2.

Fig. 4 is a section on line 4—4 in Fig. 2 with many parts omitted.

35 Fig. 5 is a section on line 5—5 in Fig. 2 with some parts omitted.

Referring to the drawings by reference numerals it will be understood that inasmuch as one side of the apparatus is a 40 counterpart of the other side a clear illustration and description of one side will answer for both.

When the apparatus is used directly in a house or dwelling place it is provided with a 45 base supporting ring 7 having integral legs 8 and the base 9 of the apparatus rests in a preferably circular recess formed by a rim 9^a of said supporting ring. But when the apparatus is used in the basement as a furnace the ring 7 is omitted and the base 9 placed directly on the floor 10, in a manner not shown but readily understood and a cylindrical top piece 11 of suitable height leads the hot air from the top 12 of the 50 heater to a register 13 in the floor 14 of the building and after the air has heated the

room or rooms above said floor 14 it returns downward as indicated by arrows 16 in Fig. 2, through a register 15 and pipe 17 into a horseshoe-shaped space 18 between the similarly shaped wall 19 of the ashpit 20 and the regular air jacket 21, taking with it more or less fresh air from a tube 22 having a valve 23 with handle 24 for regulating the intake of fresh air from outside the wall 24^a of the building.

A draft pipe 25 conveys the smoke into a chimney 26 of the building. 12^a is an ornamental top ring on the apparatus.

All these air leading pipes and parts so far described being of but common construction I have mentioned them at this time so as not to confuse them with the more novel features of my device which will now be described. This much may however also be said here, that whenever the device is used as a heater in the rooms to be heated the pipes 11, 17, 22 and registers 13 and 15 are omitted and the hot air flows into the room from a register 13^a in the top of the heater 70 and the cool air on the floor flows in under the apparatus again through the spaces 8^a between the legs 8 and is heated over again.

The invention comprises a base 9 which forms the bottom 27 for the ash pit 20 (see 85 Fig. 5) and an almost circular ridge 28 held by radial arms 29 against the inner side of the sheet-metallic air jacket 21, and is formed with large apertures 30 for the upward passage of air to be heated in the jacket. The jacket is also guided and held in central position by the projecting outer edge 31 of the bottom 32 of a horseshoe-shaped air duct or chamber 33 having its 90 rearmost extension 34 provided with a clean-out lid 35 (see Fig. 2). The top plate 36 of said air chamber has a large central opening down into the edge 37 of which is recessed the firepot 38 (see Fig. 2). The projecting top and bottom of the air chamber 33 are both formed with air passages 39 directly above each other between the air chamber and the ash chamber; and the bottom 31 also has air passages 40 outside the 95 chamber 33 it being wider than the top plate 36 above it.

The top of the jacket 21 is secured at 41 to the top ring 12 and the vertical front edges of the jacket are suitably secured in place close to the front plate or door frame 42 which is secured by screws (or bolts) 43 to the structure already partly 100 105 110

described, and is provided with several door openings, closed by hinged doors 44, 45, 46, 47, the latter door carrying two smaller doors 48, 49.

5 The doors 44 and 46 are each provided with a rocker arm 50, pivotally connected to an operating rod 51 having an enlarged portion 52 with a transverse slot 53 in it. In said slot engages a lateral pin 54 of a 10 lever 55 which is pivoted at 56 to a lug 57 on the door frame 42, so that by raising the outer end of the lever the two doors are 15 opened simultaneously to admit air for purposes presently to be described. When said lever is to be operated by a thermostat a single guided chain 58 attached to the thermostat motor will raise the lever and when the motor acts again to close the doors the 20 gravity of the doors, the lever and the rod 51 will cause the closing.

Turning now to a further description of the heater proper, the stationary grate 59 below the firepot is circular and provided with radial projections 60 which by a slight 25 turning movement of the grate are caused to engage upon inclined top surfaces of fixed lugs 61 and thus to hold the gate in a detachable manner when it is to be repaired or replaced by a new one. The ash pit 30 being of equal width all the way from its middle to the front end said upper grate may be removed and replaced by opening the large door 47. Likewise the lower grate bars 62 and their supporting ring 63 35 (see Fig. 5) may be removed, since the ring 63 rests between guiding lugs 64 projecting but slightly upward from segmental cleats 65 having lugs 66 secured by bolts 67 to the sides of the ash chamber. The ring 63 40 is provided at its front edge with a short rocker arm 68, upon which may be placed a socket wrench 69, swingable from side to side in shaking the grate bars 62; said grate bars 62 being journaled at 70 in the 45 ring and connected by meshing gears may also be rocked or partly rotated in unison by placing the socket wrench 69 on either one of the square shanks 72 of the front journals of the grates and using the portion 50 69^a of the wrench as a rocking arm.

Mounted upon the top edge of the firepot is a ring forming a practically circular air duct 73 (see Figs. 2 and 4) having a downwardly flared inlet 74 facing the door 46; 55 the inner top edge of said air duct is provided with notches 75 through which air enters (as arrows 76) into the top of the space 77 close above the fire.

Secured by bolts 78 upon the duct 73 is 60 a combustion chamber 79 having a dome-shaped top 80 with a central aperture 81 in which is held the flared top end 82 of a downwardly tapered tube 83, to the lower end of which is detachably secured by 65 L-shaped notches 84 and pins 85 (see Fig.

2) a hollow acorn-shaped air distributor 86 having lateral apertures 87 through which air passes (as arrows 88 in Fig. 4) while the air indicated by arrows 89 comes in the opposite direction whereby air is thoroughly mixed with the gas rising from the burning fuel in the fire pot; the fire also receiving air up through the grates 59 and 62 in the usual manner. The air passing downward through the tube 83 enters the apparatus through a duct 90 leading from the door 44.

The thus heated air and smoke in the combustion chamber 79 may reach the chimney 26 either in a comparatively direct way 80 as indicated by arrows 91 in Fig. 2, the smoke passing to pipe 25 through a horizontal extension 92 of the combustion chamber, or this extension may be closed by raising a valve 93 upward against a stop 94, 85 said valve having a rocker arm 95 operated by a guided rod 96 having a handle 97 at the front of the apparatus. When the valve is thus raised from the horizontal to the vertical position shown, the hot air and smoke pass out at both sides of the combustion chamber into two side chambers 98 and thence downward, as arrows 99, through tubes 100 into the air duct 33 and thence upward, as arrows 101, through a tube 102 95 into the extension 92 and pipe 25 back of the raised valve 93.

The operation of the apparatus being already described at the beginning of the specification and incidentally in the body of the same, I need here only add further that the air entering the apparatus either through the apertures 8^a or through the pipes 17 and 22 is most thoroughly heated by the large heating surfaces of the ash pit, the fire pot, the tubes 100 and chambers 98, combustion chamber 79 and its dome 80, duct 90 and tube 102 before it escapes from the jacket 21 upward through register 13^a 100 into the room where the apparatus stands, or through register 13 into rooms above the floor 14, and by such thorough utilizing of the heat a considerable amount, approximately as much as fifty percent, of the fuel used in ordinary heating devices is 110 saved.

By proper regulation of the air inlet doors 44-46, draft doors 48 and 49, and attending to the fire through the fuel intake door 45 according to the kind of fuel used, all gas from the fuel and also the coke of it will be most economically burned and all heat therefrom utilized for heating the room or rooms in the building.

I have indicated chains 58, 58^a, 58^b leading to one or more thermostats (not shown) for any desired automatic regulation of the draft doors and the valve rod 96, the latter having a bell-crank lever 58^c to facilitate its operation by chain 58^a. Some doors may 125

also has toothed segmental catches for holding them partly open as indicated by the element 58^a in Figs. 1 and 2, but as such regulating devices are well known I will not 5 fully describe or show them.

In starting a fire in this heating apparatus the damper or valve 93 should be pushed to horizontal position, the door 49 opened to let air into the base of the fuel, and the 10 doors 44 and 46 should also be opened to let air into the gas in the combustion chamber above the fire pot. The doors and valve 93 may further be regulated later on according to the fuel used and the condition of the fire 15 and the requirement of heat.

What I claim is:

1. In a device of the class described, the combination with a fire-pot and fuel grates below the same, of a gas mixing and combustion chamber over the fire-pot and means for leading air into the combustion chamber from all sides of it, and means for spreading air outward into the combustion chamber from the center of it, said combustion chamber having a horizontal rearward extension adapted to connect with a chimney or like outlet and having in its lower side an aperture and a vertical flue connected therewith, and a valve arranged to close 20 alternately the top of the flue and the passage through the horizontal extension, a horizontally curved flue embracing the greater portion of the part of the apparatus in which the fuel grates are disposed and 25 having its rear portion communicating with said vertical flue, and a vertical flue at each side of and slightly spaced from the fire-pot and having each its lower end opening into the curved flue and its top end opening into 30 the adjacent side of the combustion chamber, and means for regulating the said valve. 35 2. In a heating apparatus of the class described, a fire-pot with a gas and air mixing chamber near above it, an air duct surrounding the mixing chamber and having aper-

tures letting air in laterally from several points of the chamber, and a hinged door letting air into the duct, another hinged door higher up on the apparatus, an air duct leading from the latter door in and downward into the mixing chamber and provided with lateral outlets for air to mingle with the gas in a direction opposite to the air from the circular air duct and means for regulating the opening and closing of said two 50 doors.

3. In a heating apparatus a suitable framework with a firepot in it and below the fire-pot an ash chamber having a comparatively large door, horizontal cleats secured to 60 the inner sides of the ash chamber and having circularly arranged studs at their upper sides, a grate supporting ring resting upon the cleats and being rotatable between the studs, horizontal grate bars journaled in the 65 upper side of the ring and geared together to rotate in unison, and means for rotating the ring in a horizontal plane and the grates in a vertical plane, said ring being removable forwardly by lifting it above the studs, 70 and the door being large enough for removing and replacing the ring with the grate bars resting in the journals.

4. The structure specified in claim 2, said central duct leading air downward into the 75 chamber consisting of a downwardly tapering tube with an enlarged hollow and laterally perforated head detachably secured on its lower end.

5. The structure specified in claim 2, said 80 surrounding air duct having the portion of it adjacent the door flared out to the same size as the door opening.

6. The structure specified in claim 1, and 85 a spaced jacket encircling the said structure and having inlet for air to be heated and outlet for the heated air into the space to be heated.

In testimony whereof I affix my signature.

FRED WEINECK.
